UNITED STATES PATENT OFFICE

WALTER A. BATES, OF GARY, INDIANA, ASSIGNOR TO GARY STRUCTURAL STEEL COMPANY, OF GARY, INDIANA, A CORPORATION OF DELAWARE

GRATE MAKING APPARATUS

Application filed February 15, 1930. Serial No. 428,609.

This invention relates to improvements in the manufacture of a novel design of floor grating, and more particularly has relation to the apparatus for performing one of the several operations involved in the construction of the grating.

The completed grating is composed of a plurality of longitudinal bars supported in spaced relation and in vertical edgewise positions, and a plurality of transverse bars which are generally spaced apart a greater distance than the space between the longitudinal bars and are designed to extend through openings in the longitudinal bars. 10 The top edges of the transverse bars in the completed grating are in the same plane as the top edges of the longitudinal bars. The transverse bars rest upon uncut portions of the longitudinal bars and are provided with 15 slots downwardly extending from the top edges in order to receive the upper uncut portions of the longitudinal bars. In forming this design of grating, the operation consists in punching out slugs to form the rectangular openings in the longitudinal bars in which the transverse bars are finally seated. 20 But in order to allow the transverse bars to be inserted through the longitudinal bars and brought to the final position, it is necessary to carry out intermediate operations which 25 comprise cutting out a tongue in the longitudinal bar adjacent each opening, which may be bent normal to the longitudinal bar and thus provide a wide slot through which 30 the transverse bar may be inserted in a flat horizontal position. The transverse bar is then turned through 90° to a vertical position and the several tongues are bent back into the plane of the longitudinal bar and 35 have their ends abutting against the vertical sides of the transverse bars. In this manner, a very strong and rigid grating is formed, having no parts which will become 40 loosened through vibration and designed to give a long period of useful life.

This specification discloses a machine developed to perform the operation of bending back into place the tongues which have been turned out to allow the insertion and turning 45 of the transverse bars.

It is therefore the purpose of this invention to provide apparatus which will efficiently handle partially completed grating as it is fed therethrough and perform the final operation of turning the tongues back 55 into place.

An object of the invention consists in a construction whereby the grating may be intermittently fed through the apparatus and in which means are provided to operate while 60 the grating is stationary to bend the tongues back in place.

A particular feature of this invention consists in providing bending fingers movable vertically into association with the grating 65 and operated upon a 90° movement to turn the tongues into their final positions while at the same time backing up and holding fingers are upwardly moved into association with the grating in order to rigidly hold the 70 grating while it is operated upon.

Additional objects and advantages of the present construction will be more clearly apparent as the description proceeds in connection with the attached drawings, in which 75 a preferred embodiment is illustrated.

In the drawings, in which like numerals are used for similar parts throughout—

Figure 1 is a plan view of the apparatus with a few parts broken away;

Figure 2 is a vertical longitudinal section taken through the apparatus shown in Figure 1;

Figure 3 is a plan view showing the grating as it is fed through the apparatus and 85 illustrating the action of benders and backing up fingers;

Figure 4 is a perspective showing especially the discharge feeder and the straightening comb;

Figure 5 is a diagrammatic view illustrating the steps performed in making the grating, the step indicated at E being formed by this machine; and

Figure 6 is a fragmentary sectional view 95 illustrating the relation of the backing up fingers to the cross bars and tongues.

Before the grating is fed to the machine of this invention, the longitudinal bars 6 are punched with rectangular openings, as in- 100

dicated at A in Figure 5, to accommodate the cross-bars 8 in their final position, and these openings are enlarged by cutting and bending out tongues 10, as shown at B. Then the cross-bar is thrust through the enlarged slots, 5 as illustrated at C, and turned vertically, as indicated at D. This machine closes the tongues into place, as shown in position E.

The apparatus consists of a table 20 supported by frame 22. The table preferably has longitudinal grooves in its top to guide the grating. When the grating has been fed onto this table to the proper position, backing up fingers 24 and 25 are raised and benders 26 and 27 are lowered into engagement with the grating. The backing up fingers 24 are notched for the reception of a projecting tongue, the notch being widened at the top, as illustrated in Figure 3, to shift the grating slightly if necessary to get it exactly positioned. In this figure, it is seen that only half the tongues are flattened by benders 26, the alternate ones being engaged by fingers 24 and later flattened by benders 27. The benders 26 and 27 are cylindrical, with quarter cylinder fingers projecting downward to engage the tongues. These benders are carried by a platen 30 which slides in guideways 32 which form a continuation of the frame 22. The platen 30 is raised by means of rods 34 which extend downwardly through table 20 and are affixed to cross-beam 36 which is carried by piston rod 38. The piston rod 38 is forced upward by pressure in cylinder 40 and downward by the weight of the apparatus, which may be assisted by pressure above the piston in the cylinder 40 if desired. The platen 30 carries clamps 42 which assist in holding the grating in place when the platen is lowered onto the grating. Also attached to the cross-beam 36 is a system of levers 44 pivoted at 46 to a support fixed to table 20. This system of leverage raises the fingers 24 by any convenient means, at the same time that the platen is lowered. A similar but reversed system raises the fingers 25 at the same time.

When the fingers thus raised hold the grating in place, as illustrated in Figure 3, the 10 downwardly extending fingers of benders 26 and 27 are located behind the tongues, that is, in the angle of the tongues. As clearly shown in Figure 3, a rotation of the benders 26 and 27 counterclockwise about a point in the angle of the tongues will flatten the 15 tongues in place. These benders extend through the platen 30 and at their upper end are keyed to cranks 48 carrying pins 49 projecting into slots in the slides 50 which are reciprocated by the cylinders 52, as clearly indicated in Figure 2. It is clear that this reciprocation rotates the benders 26 and 27 to bend the tongues into place.

The backing up fingers both hold the grating 20 from motion and back up the longitudi-

nal members against the turning force of the bender. However, this backing up effect is not quite sufficient to prevent a slight distortion of the longitudinal members of the grating. This slight distortion tends to give 70 to the grating as a whole a slight curve. Means is therefore provided for avoiding or removing this curve. This consists primarily of a comb 56, the teeth 58 of which contact with each of the longitudinal members 75 of the grating. The comb 56 is slidably mounted to the platen 30 by bolts 59. This comb is thrust laterally in a direction to straighten the grating by means of a cam 60 (Figure 4) mounted on a shaft 62 which is 80 turned by the crankarm 64 which is actuated by the cylinder 66. The comb is partially returned to its original position by the return action of the grating, and any additional return means, such as a spring, may 85 be used if desired.

The grating is fed intermittently by the feeding fingers 70 and 72 which are pivotally supported on shafts 74 and which press against the cross-bars 8 in the active stroke 90 and are pressed down by the action of said cross-members on the slanting rear face of said fingers 70 on the return stroke. The fingers 70 and 72 may be normally pressed upwardly by means of a spring or counterweight, not shown. The shafts 74 are mounted on slides 76 and 78 respectively which slide on frames 80 and which are connected and maintained parallel by two spaced rods 82. The slide 78, and therefore with it the slide 76, is maintained perpendicular to the longitudinal members of the grating by means of a rack 84 at both extremities of the slide 78, said racks cooperating with pinions 86 keyed to common shaft 88. The desired reciprocating motion is imparted to this feeding mechanism by the cylinder 90 acting through piston rod 92. Automatic valves are of course provided for timing the actuation of the various cylinders. These 105 have not been shown as many possible constructions are well known.

The operation of the apparatus is as follows:

Piston 90 operates the feeder fingers 70 to 115 press against the cross-members 8 to shove the grating into place. Then the cylinder 40 is automatically actuated to let or force down the platen 30 carrying the benders 26 and 27 into place behind the tongues and at the same time to raise the backing up fingers 24 and 25 into place opposite the benders 26 and 27 respectively. As previously stated, the fingers 24 coact with some 120 of the tongues to insure the proper positioning of the grating while the other tongues are being bent by the benders 26. The grating is further held by the clamps 42 which are especially helpful in holding the longi- 125 130

tudinal members which are not held directly by fingers 24.

As soon as the platen has been lowered into position, the cylinders 52 are actuated to reciprocate the slides 50, turn the crankarms 48, and rotate the benders 27, thus bending the tongues 10 tightly into place and firmly anchoring the cross-members 8. When the feeders have again been reciprocated twice more, the row of tongues which has been acted upon by the benders 26 is placed in position to be acted upon by benders 27. Benders 27 and 26 are in staggered relation so that the benders 27 flatten into place those 15 tongues which had not been flattened by benders 26. Preferably at the same time, cylinder 66 is actuated to rotate the cam 60 and thus laterally force comb 56 to straighten out the grating and thus overcome the 20 curving effect of the benders.

It is to be understood that many other embodiments of the invention, including some in improved form, will be apparent and in the course of time will be devised by those 25 skilled in the art. My invention includes all of these which come within the spirit of the following claims, construed as broadly as the prior art will permit.

I claim:

30 1. In apparatus for making grating in which a tongue on the longitudinal members of the grating is bent to hold the transverse members in place, means for holding said grating in the desired position, and means 35 for simultaneously bending a plurality of said tongues.

2. In apparatus for making grating in which tongues on the longitudinal members are bent to hold the transverse members in 40 place, means for holding the grating with said tongues in a given position, and means rotatable about the point of connection of said tongues with said longitudinal members to bend said tongues.

45 3. In apparatus for making grating in which tongues on the longitudinal members are bent to hold the transverse members in place, means for holding the grating with said tongues in a given position, and means 50 rotatable about the point of connection of said tongues with said longitudinal members to bend said tongues, said members having a pressure face of about the same length as the tongue.

55 4. In apparatus of the character described, means for progressing a grating to approximately the desired position, means insuring the location of said grating exactly in said position, and means for bending a tongue on some of the members of the grating to hold the other members of the grating in place.

5. In apparatus of the character described, means for holding the grating in a desired 60 position, and means for simultaneously bending tongues on some of the members of said

grating to hold other of the members of said grating in place.

6. In apparatus of the character described, means for progressing a grating approximately to a desired position, means for insuring the exact positioning of said grating, 70 means for holding the grating in said position, and means for bending the tongues of some of the members of said grating to hold other of the members of said grating in position.

7. In apparatus of the character described, means for progressing a grating approximately to a desired position, means for insuring the exact positioning of said grating, 80 means for holding the grating in said position, and rotatable means for bending the tongues of some of the members of said grating to hold other of the members of said grating in position.

8. In apparatus of the character described including means for progressing grating to a desired position, means for holding the grating in said position, and means rotatable to bend a tongue on some of the members of said grating into position to hold other members of said grating in place.

9. In apparatus of the character described for bending the tongues of certain members of the grating in place, means for advancing said grating to place said tongues in a desired position, means for holding said grating with the tongues in said position, and means rotatable about a point approximately in the intersection of said tongue and the member of which it is a part to bend said tongue.

10. In apparatus of the character described, means for bending a tongue into position to hold the parts of the grating in proper relation, and means for counteracting the tendency of said bending means to curve the grating as a whole.

11. In apparatus for making grating in which a tongue on some of the members of the grating is bent to hold other members of the grating in place, means for advancing the grating to a desired position, means for holding the grating in said position, means for bending the tongue in said grating, and means for counteracting the tendency of said bending means to curve the grating as a whole.

12. In apparatus for making grating in which a tongue on some of the members of the grating is bent to hold other members of the grating in place, means for advancing the grating to a desired position, means for holding the grating in said position, means for bending the tongue in said grating, and means for counteracting the tendency of said bending means to bend the grating in any undesired manner.

13. In apparatus for making grating in which a tongue is bent to hold the parts of

- the grating in proper relation, means for bending the tongues on the members running in one direction, said means having the effect of curving said members, a comb fitting against each of said members, and means for moving the comb to bend said members in a direction an amount that will leave said members straightened. 75
14. In apparatus for bending straight tongues which project laterally from members of a grating, means straddling some of said tongues for holding the grating in place, and means for bending straight the other of said tongues. 75
15. In apparatus for bending straight tongues which project laterally from members of a grating, means coacting with some of said tongues for holding the grating in place, and means for bending straight the other of said tongues. 80
16. In apparatus for making grating in which the grating supplied to a machine consists of a plurality of longitudinal members having slots therein, a plurality of transverse members in said slots, tongues projecting from one end of said slots, means for advancing the grating to a desired position, said means consisting of members which contact with the transverse members and move them to a desired position, and means to bend the tongues against the transverse members. 85
17. In apparatus for making grating by bending tongues projecting from some of the members of said grating to hold the other members of said grating in place, means for advancing the grating in its plane to a desired position, holding means and bending means movable into contact with said grating, and means to operate said bending means. 95
18. In apparatus for making grating by bending tongues on some of the members of said grating into position to hold other members of the said grating in place, means for moving said grating horizontally to a desired position, means movable in one direction vertically to hold said grating in place, and means movable in the other direction to contact said tongues and also movable to bend said tongues. 105
19. In apparatus of the character described, means for advancing the grating to a desired position, means for bending a tongue on some of the members of said grating into position to hold cross members of said grating in place, and an anvil for holding said grating in said position and for backing up said first mentioned members to resist the bending force. 110
20. In apparatus of the character described, means for advancing the grating to a desired position, means for bending a tongue on some of the members of said grating into position to hold cross members of said grating in place, and an anvil movable 115
- 120
- 125
- 130
- into the plane of said grating for engaging tongues on another of said members and to pick up said first named members to resist the bending force.
- Signed at Gary, Indiana, this 10th day of February, 1930.
- WALTER A. BATES.
